LEON EDELSON, OF PHILADELPHIA, PENNSYLVANIA, ASSIGNOR TO EDWARD G. BUDD MANUFACTURING COMPANY, OF PHILADELPHIA, PENNSYLVANIA, A CORPORATION OF PENNSYLVANIA

LATCH MECHANISM

Application filed November 11, 1926, Serial No. 147,647. Renewed February 11, 1931.

This invention relates to a latch mechanism particularly adapted for use upon doors of closed automobile bodies, although it could be used in other relations.

5 In order to permit of the use of a window substantially of the full width of the door, latch mechanisms have been used on automobile doors wherein the outside latch operating devices are connected to the latch 10 bolts by means circumventing an edge of the window in such manner, that the jamb edge thereof may lie substantially against or adjacent to the jamb edge of the door. A maximum of vision from the interior of 15 the closed body is thus obtained.

The main object of this invention is to provide a latch mechanism, wherein the connection between the latch bolt and the outside latch operating device permits the use 20 of a window of substantially the full width of the door, which is simple, inexpensive, efficient, and capable of application to the door in an easy manner that does not necessitate extensive alteration thereof.

25 Further objects and advantages will become apparent with the further description hereinafter following.

The manner in which the objects of the invention may be attained will be made clear 30 by showing and describing a specific embodiment thereof.

The figures of the drawings are, as follows:

35 Fig. 1 is a horizontal section view through a door and door post, showing the latch mechanism in the top plan.

40 Fig. 2 is a side elevational view of the jamb face of the door and latch mechanism, the keeper being shown, however, to indicate the relationship of parts; and

45 Fig. 3 is a diagrammatic view of the latch mechanism in latched and unlatched positions.

The latch mechanism is disclosed as being mainly within the well or pocket 1 of the door of a closed automobile body. A sliding window 2 is also within such well or pocket in most positions of the window.

50 In accomplishing the provision of a latch mechanism having the desirable character

istic of simplicity, it is contemplated to use an integral latch member, forming not only the latch bolt but also the interconnecting or interlocking member between the outside and inside latch operating devices. This 55 latch member comprises two aligned arms 3 and 4 spaced apart as at 5. Extending outwardly toward the jamb face of the door from the spaced apart ends of the aligned arms is a substantially U-shaped member having legs 6 and 7 connected respectively with the ends of the arms 3 and 4, and a bight portion 8. The legs 6 and 7 extend past the jamb edge of the door through an 60 elongated opening 9 in the jamb face thereof. The bight portion 8 lies beyond the plane of the jamb face of the door. The free ends of the aligned arms are journaled in the outer and inner door panels 10 and 11, respectively, whereby the latch member 65 may be bodily oscillated. It will be apparent that the slot 9 affords clearance for the outer ends of the legs 6 and 7, and for the bight 8, during such oscillatable movement. The bight 8 forms the latch bolt and is 70 adapted to engage behind a keeper 12, on the door post, when at the limit of its movement in one direction. It should be observed here that the ends of the slot 9 serve 75 to limit the oscillatable movement of the latch member. The keeper is provided with a two faced cam surface so that the latch bolt will ride over and drop down behind the keeper upon slamming of the door.

In the journaling of the free ends of the 80 latch member in the inner and outer door panels any suitable means may be used. The method followed in the present instance is to provide a supporting or reinforcing plate 13 having portions lying adjacent the outer, inner, and jamb faces of the door paneling. The ends of the latch member pass through apertures formed in the supporting plate and the door panels. In the drawings a bushing 14 is shown as being 85 used for one of the ends. The projecting ends of the latch member are secured to suitable handles in any well known manner. The inner handle 15 is shown in the drawing as being of one type, while the outer 90 handle is of another. The outer handle 16 is 95 secured to the outer end of the latch member.

handle 16 is shown as being of another type. An escutcheon ring 17 completes the appearance of the door.

It is not necessary to use a spring in the mechanism, since gravity will efficiently return the bolt to keeper engaged position. However, the employment of a spring to supplement the force of gravity is preferable since such spring could also be capable of retaining the bolt against rattle.

The operation of the latch mechanism is thought to be obvious from the foregoing description. When either of the operating handles are turned in a counter clockwise direction the latch member moves bodily and the bight 8 is lifted above the keeper 12. The operating handles being released the latch member will move in the reverse direction until the limit of the slot 9 is reached. This return movement may be obtained solely by gravity or also by the use of a spring. If the door is slammed the lower edge of the bight 8 will engage the cam surface of the keeper and ride up over the same, falling therebehind.

A latch mechanism according to that described comprises a minimum number of parts. The latch member proper being an integral member may be inexpensively produced as a casting. The spaced legs 6 and 7 provide an ample space for the accommodation of the window glass 2, enabling such glass to extend substantially to the jamb edge of the door. The ease with which the mechanism may be attached to the door, as well as other advantages, are so apparent that reference thereto is unnecessary.

Where I have used herein and in the following claims, the expression "a window of substantially the full width of the door", or a similar expression, it has reference more particularly to the relative extent of the door and sliding window at the latch side of the door, with which my invention is more particularly concerned.

The invention, of course, is susceptible of various modifications and adaptations within the scope of the appended claims.

What I claim is:—

1. In a latch mechanism for an automobile door having a window of substantially the full width of the door slidable therein, inside and outside latch operating devices extending inwardly of the door in opposite directions to points adjacent to the window on opposite sides thereof, and a latch of substantially U-shape having its bight portion lying without the plane of the jamb face of the door and its arms extending inwardly of the jamb face and embracing said window, the inner ends of said arms and the inner ends of said operating devices being respectively connected together.

2. In a latch mechanism for an automobile door having a window of substantially

the full width of the door slidable therein, inside and outside latch operating devices extending inwardly of the door in opposite directions to points adjacent to the window on opposite sides thereof, and a latch of substantially U-shape having its bight portion lying without the plane of the jamb face of the door and its arms extending inwardly of the jamb face and embracing said window, said latch and said operating devices being integrally joined together.

3. In a latch mechanism for an automobile door having a window of substantially the full width of the door and slidable therein, an integral latch bolt member having spaced end portions arranged on opposite sides of the window and extending outwardly in opposite directions for connection with operating handles and a substantially U-shaped portion extending at right angles from the inner ends of the end portions.

4. In a latch mechanism for an automobile door having a window of substantially the full width of the door slidable therein, an integral member having spaced end portions extending in opposite directions and a substantially U-shaped portion extending at right angles from the inner ends of the end portions, the outer end of each end portion being oscillatably journaled in the inner and outer sides of the door respectively and the outer end of the U-shaped portion lying without the jamb face of the door.

5. In combination with the door of an automobile of the type having a window of substantially the full width of the door slidabale therein and a door post, a latch mechanism, said mechanism comprising a substantially U-shaped member having portions extending in opposite directions from the ends of its arms, said portions being journaled in the outer and inner sides of the door, and a keeper on the door post adapted to be engaged by the bight portion of the U-shaped member.

6. In combination with the door of an automobile of the type having a window of substantially the full width of the door slidabale therein and a door post, a latch mechanism, said mechanism comprising a substantially U-shaped member having portions extending in opposite directions from the ends of its arms, said portions being journaled in the outer and inner sides of the door and having operating handles attached to their outer ends, and a keeper on the door post, whereby when said operating handles are turned the bight portion of said U-shaped member will have oscillatable movement to and from keeper engaged position.

7. In a latch mechanism for an automobile door having inner and outer panels and a window of substantially the full width of the door and slidabale therein, inside and outside latch operating devices secured to

the inside and outside door panels respectively, and a latch portion rigidly connected to the inner ends of said devices and straddling the edge of the window.

- 5 8. In a latch mechanism for a vehicle door having a window of substantially the full width of the door slidable therein, inside and outside latch operating devices extending inwardly of the adjacent lateral faces
- 10 of the door toward the plane of the window, and a latch of substantially U-shaped having its bight portion lying without the main body of the door at a vertical edge thereof and its arms extended inwardly through the
- 15 vertical edge of the door and embracing the vertical edge of the window, said arms being, respectively, operatively connected to the inside and outside operating devices.

9. In a latch mechanism for a vehicle door
- 20 having a window of substantially the full width of the door slidable therein, inside and outside latch operating devices, and a U-shaped pivoted latch bolt straddling the edge of the window, and having its bight
- 25 portion arranged beyond the main body of the door at a vertical edge thereof and its arms passing through the edge of the door into the interior thereof on opposite sides of the window, said inside and outside operating devices being connected with said latch bolt to actuate it.

10. In a latch mechanism for a vehicle door having a window of substantially the full width of the door slidable therein, inside and outside latch operating devices, and a U-shaped latch bolt pivoted on a horizontal axis straddling the edge of the window, and having its bight portion arranged beyond the main body of the door at a vertical edge thereof and its arms passing through the edge of the door into the interior thereof on opposite sides of the window, said inside and outside operating devices being connected with said latch bolt to actuate it.

In testimony whereof he hereunto affixes his signature.

LEON EDELSON.
